UNITED STATES PATENT OFFICE.

BARNEY GOLDMAN, OF NEW YORK, N. Y.

SNOW-MELTING APPARATUS.

1,391,889.

Specification of Letters Patent. Patented Sept. 27, 1921.

Application filed March 8, 1920. Serial No. 384,059.

To all whom it may concern:

Be it known that I, BARNEY GOLDMAN, a citizen of the United States, residing at New York, in the county of New York and State of New York, have invented new and useful Improvements in Snow-Melting Apparatus, of which the following is a specification.

This invention relates essentially to an apparatus for melting, scooping, and sweeping snow and it provides means mounted on the frame or platform of a truck carrying the melting devices for storing and generating the combustible employed in melting the snow.

The object of the invention is to control the flow of the combustible to the various coils having the burner tubes so that when desired the heat can be cut off from any section of the coils.

Another object of the invention is to provide the coils with downwardly positioned pipes arranged with their nozzles pointing in the direction of travel to direct the flame toward a bank of snow.

Another object of the invention is to provide a scooping device operated by the propelled snow melting truck, whereby the soft snow and refuse is elevated from the ground into a wagon trailer connected to the snow melting device.

Another object of the invention is to provide a motor conveniently mounted on the truck frame adjacent to the combustible tank for propelling the truck.

The invention resides in the novel combinations hereinafter described and claimed, reference being made to the accompanying drawing in which:

40 Figure 1 represents a sectional side elevation of an apparatus embodying this invention.

Fig. 2 is an inverted plan view of the snow melting truck.

45 Fig. 3 is a transverse section taken along the line 3—3 of Fig. 1.

In the drawing is shown a truck including front and rear wheels 5 each having an axle 6 secured by means of hangers 7 to the platform or frame 8 of the truck. On the platform is secured a motor 9 driven by gasoline or other fuel. The motor has a belt and pulley connection 10 with a pulley 11 on the rear axle for propelling the vehicle. On the platform alongside of the motor is mounted a tank 12 for generating carbid. A coil 13

is arranged below the platform and it is connected to the tank by means of a feed pipe 14 having a valve 15 for controlling the flow of the gas from the tank to the coil. 60 From the bottom of the coil project a series of nozzles 16 having inclined or angular portions to point in a direction in which the vehicle is traveling. Arranged inside of the said coil is another coil section 17, best seen 65 in Fig. 2. The latter is connected to the main pipe by means of a branch pipe 18 as indicated in Fig. 3, provided with a valve 19 to govern the flow of gas to the inner coil. The inner coil has nozzles similar to nozzles 70 on the outer coil and pointing in the direction in which the vehicle is moving.

It will be understood, from the foregoing that the outer and inner coils are independent of each other in view of the fact that 75 when the valve 19 of the branch pipe is shut, it will eliminate the inner coil without interfering with the outer coil. The valve 15 controls the volume of gas from the tank to both coils. This arrangement permits one 80 coil to be put out of action when desired, while the other coil can remain in action. Any number of the coil sections and nozzles can be provided and as shown the flame at 85 the end of a nozzle is directed toward the pile of snow while the truck is moving forward.

In order to prevent any heat from the nozzles striking the platform and the wheels of the truck, a sheet of asbestos 20 is arranged between the platform and the coils. The sheet has side members 21 extending downwardly to prevent the flame from injuring the wheels and other bearings. The axles can also be covered with a non-conductor of heat 22 where they are exposed to the flame.

At the back of the snow melting truck is positioned a vertical carrier consisting of an endless belt or chain 23 engaging an upper roller or sprocket 24 and a lower roller or sprocket 25. The sprocket 25 is rotated in the proper direction by a cross belt 26 in engagement with a drive pulley 27 mounted on the rear axle of the truck. The endless belt has secured to it a series of buckets 28 made to scoop up any soft snow or dirt left from the melting snow or ice, elevate it and drop it into the body of a wagon 29 rolling behind the carrier. The frame 30 of the carrier is fastened to the forward part of the wagon and the wagon is hooked by re-

movable bars 31 to the truck. A brush 33 to sweep up the remainder of the dirt is mounted below the body and it is connected to the rear wheel by a belt 34 to rotate it 8 when the wagon is moving. When it is desired to use the melting apparatus without the trailer, the latter can be removed by unhooking the bars.

It will be understood that the truck may 10 be attached or hooked to the front of a trolley car, railroad train or automobile, and various changes may be made in the position of the heat generating means or driving mechanism without departing from the principle of this invention.

I claim:

1. A snow melting apparatus comprising a truck having a frame, means for propelling the truck, a fuel tank mounted on the 20 frame, a plurality of coils connected to the tank secured to the frame, each coil being independent of the other, a main pipe connecting the coils with the tank, a branch pipe leading from the main pipe to a coil, a valve

on the main pipe for controlling the volume 25 of fuel admitted to each coil, a valve controlling the flow of fuel from the main pipe to the branch pipe, and a series of burner tubes projecting downwardly from the coils.

2. A snow melting apparatus comprising 30 a truck having a frame, a fuel generator mounted on the frame, a plurality of coils connected to the generator arranged under the frame, each coil being independent of the other, means for controlling the volume 35 of fuel admitted to each coil, a valve for shutting off one of the coils, and a series of nozzles projecting downwardly from the coils with angular portions to point in a direction of the travel of the truck.

In testimony whereof I have hereunto set my hand in the presence of two subscribing witnesses.

BARNEY GOLDMAN.

Witnesses:

SAMUEL LEWIS,
WILLIAM MILLER.
